UNITED STATES PATENT OFFICE.

JOHN BUCKLEY, OF ROCHESTER, NEW YORK, ASSIGNOR TO THE ROCHESTER AUTOMATIC LUBRICATOR COMPANY, OF SAME PLACE.

LUBRICATOR.

SPECIFICATION forming part of Letters Patent No. 590,297, dated September 21, 1897.

Application filed January 2, 1897. Serial No. 617,819. (No model.)

To all whom it may concern:

Be it known that I, JOHN BUCKLEY, of Rochester, in the county of Monroe and State of New York, have invented certain new and useful Improvements in Lubricators; and I do hereby declare the following to be a full, clear, and exact description of the same, reference being had to the accompanying drawings, forming a part of this specification, and to the reference-numerals marked thereon.

My present invention relates to lubricators particularly of the kind known as "force-feed," and it has for its object to provide means whereby several engines or machines may be supplied with lubricant from a single lubricator and the quantity of oil fed to each regulated to a nicety. Heretofore it has been customary to provide a separate lubricating device for each engine or portion of a machine to be lubricated or else a single lubricator, usually one operated by the condensation of steam, supplying several machines or parts, but in the latter not only is difficulty encountered in subdividing the lubricant and particularly proportioning it for the various devices, but the supply is not dependent upon the actual running of the part itself or that to which it is connected, and, on the other hand, it is not always convenient to apply a lubricator and to operate it from the machine to which it is connected.

In my device I provide a single construction embodying one movable part operated from any convenient prime mover, as the engine itself, and connected with this part are independently-adjustable feeding devices, as pumps, so that by means of the adjustments the operator can regulate not only the exact quantity that is required for any moving parts without stopping the operation of the movable part or device, but the frequency with which this quantity is supplied.

The invention consists in certain improvements whereby the above objects are carried out, and also in certain details of construction, all of which will be more fully stated in the claims at the end of this specification.

In the drawings, Figure 1 is a front elevation of a lubricator containing my improvements, a portion of the actuating-wheel being broken away; Fig. 2, a vertical sectional

view through the pistons of the pumps, showing the actuating-cam; Fig. 3, a horizontal sectional view taken just above the pump-cylinders; Fig. 4, a vertical sectional view on the line $z z$ of Fig. 1; Fig. 5, a similar view on the line $y y$ of Fig. 3; Figs. 6 and 7, detail views of the clutch device for actuating the pump, and Figs. 8 and 9 similar views of a modification.

Similar reference-numerals in the several figures indicate similar parts.

The main frame of the lubricator embodies a cup or reservoir 1 for the lubricant, having a suitable cover 2, and formed upon one side of the base thereof is an enlargement in which are formed (preferably by boring vertically into the enlargement) two or more cylinders 3, in which operate pistons 4, passing through suitable stuffing-boxes formed in removable caps 5, screwing into said base. In the present instance I have shown two pistons 4, each provided with a ring or stop 6, and their upper ends pass through apertures formed in a movable member, as a cross-head 7, pivotally connected to the lower end of a pitman 8, the upper end of the latter being strapped to a cam 9, formed upon or secured to the inner side of a driving-wheel 10, pivoted upon a bolt or pin 11, secured to the side of the cup or reservoir, so that as the wheel is rotated in the direction indicated by the arrow in Fig. 1 the cross-head 7 will be moved vertically. The connection between the cross-head 7 and the pistons is formed by lock-nuts 12, screwing on the upper ends of the pistons above the yoke, which nuts may be adjusted so as to regulate the space between the lower one and the collar 6, whereby as the cross-head is reciprocated the stroke of either or both of the pistons may be regulated by adjusting the nuts nearer to or farther from the collar 6. In the embodiment shown the piston to the left is connected rigidly with the yoke by screwing the nuts 12 down upon it, while the nuts on the piston on the right are adjusted some distance from the collar 6, allowing the cross-head to play on the rod and only engage it at its extreme upward and downward movements, thereby making a very short stroke of the piston and, as will be seen, forcing but very little oil. The pistons are of such nature

and the friction between them and the cross-head is so slight that they will remain in position until operated positively by the cross-head engaging the nuts or the collars 6. Each 5 of the cylinders has in its lower end a valve-seat 13, upon which rests a ball 14, and beneath this is a smaller valve-seat 15, upon which rests a ball-valve 16, said seats being formed by boring in from the top with drills 10 of different diameters, the countersink at the end of the drill forming the seat.

17 17 indicate inlet-passages from the interior of the reservoir to the bottom of the cylinder beneath the valve 16, and which are bored from the outside, the outer ends of said 20 passages being closed by screw-plugs 18.

19 indicates discharge-passages from the pump-cylinders above the valves 14, the vertical portions of said passages being provided 25 with valve-seats of different diameters formed by boring, as described, with which co-operate ball-valves 20 and 21, and above said valves the passages are continued in the form of pipes or conduits 22, leading to the machines or surfaces to which it is desired to supply the lubricant. By forming the valve-seats of different diameters I am not only enabled to cheapen the construction of the apparatus materially, but also to employ double 30 check-valves, which I find are particularly advantageous, in that both valves of the pair are not liable to become clogged at the same time by dirt or sediment, so that the proper feed of the lubricant is assured.

35 The means employed for rotating the cam 9 may be of any suitable construction, but I prefer to actuate the wheel 10, to which the cam is connected, by means of a clutch on the end of a lever 25, pivoted on the bolt or pin 40 11 and having the slotted lower end connected by adjustable links 26 27 with a slotted lever or rock-arm 28, actuated by a reciprocating connecting-bar 29, secured to the block 30, adjustable in the slot of the arm 28, this adjustable connection being substantially the same as that contained in Letters Patent No. 564,503, granted July 21, 1896, to Maguler Butler; but any other suitable form of actuating device could be employed. The adjustment 45 between the reciprocating rod 29 and the lever enables me to regulate the speed of the wheel 10, and the adjustment between the cross-head 7 and pistons to regulate the length of stroke of the latter, and thereby the 50 quantity of oil fed at each reciprocation.

55 The particular construction of clutch device I prefer is shown in Figs. 6 and 7, the periphery of the wheel 10 being formed with a groove 10^x and the end of the arm 25 with 60 a tapering grooved recess, in which operates the ball 25^x, so that the movement of the arm in the direction of the arrow, Fig. 1, will clamp the ball between the recess in the arm and the groove in the wheel and turn the latter, the ball loosening itself as the lever is moved in the opposite direction.

In Figs. 8 and 9 in lieu of the ball a roller

25^y is shown held in place by a plate 25^z and adapted to grip the face of the wheel 10, which may be plain, or ratchet devices, such 70 as shown in the Butler patent above referred to, could be employed for the same purpose.

35 indicates a gage for indicating the quantity of oil remaining in the receptacle or reservoir. 75

The operation of the device will now be understood. The pipes 22 being connected to the journals or other parts to be lubricated and the rod 29 being connected to and reciprocated by the engine or other prime mover the 80 wheel 10 will be actuated in the direction indicated and at the speed desired, causing the pistons to be reciprocated, drawing oil from the reservoir through the conduits 17 and valves 14 and 16 to the cylinders during the 85 upward movement of the pistons, and as the latter move down the oil in the cylinders will be discharged into the passages 19 and pipes 22. If only a small quantity of oil is to be forced to one of the 90 pipes, the connection between the piston controlling it and the cross-head is loosened by moving up the nuts 12, as shown at the right in Fig. 2, so that the cross-head will only actuate the piston at the extremes of its movement and the stroke 95 will be very short.

If desired, a greater number of pistons can be actuated from a single cross-head, and the adjustments described being employed one device could supply several machines. If 100 only one of the pumps is to be used, one of the pistons may remain stationary or be rigidly secured—as, for instance, by tightening the packing by screwing down the gland—and in the construction shown it would then 105 serve as a guide for the cross-head 7, while the connection between said cross-head and the piston that is actuated may be regulated to feed the desired quantity of lubricant.

This apparatus is much more accurate than 110 a condensing sight-feed lubricator and, as will be understood, can be employed for feeding oil to pipes containing steam under pressure.

I claim as my invention—

1. In a lubricator, the combination with the reservoir, the cylinder outside of the latter, having the inlet-passage leading from the cylinder, the check-valve therein, and the exit-passage having the check-valve therein, of the piston operating in the cylinder, the reciprocating cross-head having a constant stroke, and the relatively-adjustable stops between opposite sides of the head and the piston, whereby the stroke of the piston may 125 be adjusted to any portion of that of the head, substantially as described.

2. In a lubricator, the combination with the reservoir, of the two cylinders outside of the reservoir, inlet and exit passages for the 130 cylinders, and check-valves therein, the two pistons operating in the cylinders, the reciprocating cross-head, and the relatively-adjustable stops on each of the pistons with

which the cross-head engages, substantially as described.

3. In a lubricator, the combination with a reservoir, two pump-cylinders having supply and discharge passages and valves therein, of a reciprocating member, as a cross-head, two pistons operating in the cylinders having the collars and adjustable nuts thereon, co-operating with the member, whereby the stroke of the pistons may be independently regulated, substantially as described.

4. In a lubricator, the combination with a reservoir, two pump-cylinders having supply and discharge passages and valves therein, of the rotary cam, the pitman actuated thereby, the cross-head pivoted to the pitman, the two pistons operating in the cylinders and upon which the cross-head is guided, and adjustable connections between the pistons and cross-head for regulating the stroke of the former relative to the stroke of the latter, substantially as described.

5. In a lubricator, the combination with the reservoir, the cylinder, and the piston operating therein, of an oil-passage communicating with the cylinder and having two diameters, the upper being the larger, a countersunk valve-seat at the lower end of the larger diameter, and a countersunk valve-seat at the lower end of the smaller diameter, and the large and small check-valves co-operating with said seats, both capable of introduction through the larger diameter, substantially as described.

35 6. In a lubricator, the combination with the reservoir, a pump-cylinder, inlet and discharge passages and valves therein, of the piston operating in the cylinder, the reciprocating

member, as a cross-head, adjustable slip connections between the piston and reciprocating member for regulating the length of stroke of the former relative to the length of stroke of the latter, the cam-wheel actuating the member, an actuating device for the cam-wheel, as rod 29, and adjustable connections between said actuating device and the cam-wheel, whereby the speed of the cam-wheel may be adjusted relative to the speed of the actuating device, substantially as described.

7. In a lubricator, the combination with the reservoir, two pump-cylinders, inlet and discharge passages and valves therein, and pistons operating in the cylinders, of a rotary cam-wheel, a reciprocating member, as a cross-head, actuated from the cam-wheel, independent adjustable slip connections between each of the pistons and said member for regulating their stroke relative to the length of stroke of the member, actuating devices, as a rod 29, for rotating the cam-wheel, and adjustable connections between said actuating devices and the wheel, whereby the speed of the cam-wheel may be changed, substantially as described.

8. In a lubricator, the combination with a reservoir, a cylinder, inlet and discharge passages and valves therein, of a reciprocating member, as a cross-head, having the aperture, the piston operating in the cylinder and having the collar, and the adjustable nut thereon for co-operating with opposite sides of the member, substantially as described.
